(57) **CLAIM**

The ornamental design for a finger ring cosmetic container having a heart shaped receptacle, as shown and described.

DESCRIPTION

FIG. 1 is a perspective view of the finger ring cosmetic container having a heart shaped receptacle of the present invention showing a cosmetic receptacle having a cover in its closed position;

FIG. 2 is a perspective view of the finger ring cosmetic container having a heart shaped receptacle of the present invention showing a cosmetic receptacle having a cover in its open position;

FIG. 3 is a front end elevational view showing the cover in its closed position;

FIG. 4 is a side elevational view showing the cover in its closed position;

FIG. 5 is a back end elevational view showing the cover in its closed position;

FIG. 6 is a top plan view showing the cover in its closed position and a cosmetic receptacle having a heart shape; and,

FIG. 7 is a bottom plan view showing the cover in its closed position.
